UNITED STATES PATENT OFFICE.

RUFUS D. KING, OF BOWMAN, GEORGIA.

SAW-JOINTER.

SPECIFICATION forming part of Letters Patent No. 605,550, dated June 14, 1898.

Application filed December 16, 1897. Serial No. 682,123. (No model.)

To all whom it may concern:

Be it known that I, RUFUS D. KING, a citizen of the United States, residing at Bowman, in the county of Elbert and State of Georgia, have invented certain new and useful Improvements in Saw-Jointers; and I do declare the following to be a full, clear, and exact description of the invention, such as will enable others skilled in the art to which it applies to make and use the same.

My invention relates to a novel form of saw-jointer; and the object is to provide a simple, inexpensive, and effective device for accurately jointing or striking the teeth of circular and reciprocating saws.

To this end the invention consists in certain features of construction and combination of parts, which will be hereinafter more fully described and claimed.

The accompanying drawings show my invention in the best form now known to me; but many changes in the details might be made within the skill of a good mechanic without departing from the spirit of my invention as set forth in the claim at the end of this specification.

In the accompanying drawings the same reference characters indicate the same parts of the invention.

Figure 1 is a side elevation of my improved saw-jointer. Fig. 2 is a front elevation of the same. Fig. 3 is a transverse section through one of the parallel arms on the line of one of the thumb-screws.

1 represents an approximately U-shaped casting comprising the yoke 2 and the integral parallel arms 3 4, between the inner parallel edges of which is formed the longitudinal slot 5.

6 6 denote alined shoulders formed at the upper ends of the inner edges of the arms to form a support for the jointing-file 7, which is removably fixed thereon by means of the set-screw 8, adjustably secured to the yoke 2, so as to secure the file at a right angle to the arms.

9 and 10 represent guide-plates adjustably secured to the arms 3 and 4 by the thumb-screws 11 12 and 11' 12'. The orifices 13 13' in these guide-plates are considerably larger

than the shanks of the thumb-screws, so as to permit of their lateral and longitudinal adjustment. The collars 14 on these thumb-screws are of sufficient diameter to take a firm bearing on the face of the guide-plates 55 on each side of their respective orifices, and thus firmly secure the guide-plates to the arms in the position in which they have been adjusted. These guide-plates are laterally adjustable to increase or diminish the width of 60 the slot 5 to correspond to the thickness of the saw-blade, and longitudinally adjustable, so as to be extended beyond the ends of the arms 3 4 to conform to the length of the teeth to be jointed.

Should it be necessary to joint a saw in which all or some of the teeth were longer than the arms 3 and 4, the guide-plates are extended below the bottom of the teeth, so that their lower ends will have a bearing on 70 the solid body of the saw and the operation conveniently and satisfactorily performed. Another feature of this construction is that these guide-plates being independently adjustable at each end the lower ends or edges 75 of the guide-plates may be made to converge with reference to each other, so as to snugly fit a hollow-ground saw or one in which the back is considerably thinner than the toothed edge, and, as all circular saws are ground in 80 this way, this form of jointer is particularly adapted to this style of saw.

The file-blade 7 is reversible, and of course removable as well, and a suitable piece of emery-stone can be used in its stead on circular saws to joint the teeth to the same length. One side of the file-blade is preferably cut coarse and the other fine for use on saws with small teeth.

It will be observed that the space between 90 the parallel walls of the yoke above the shoulders 6 6 is considerably greater than the width of the file, so that the file-blade may be adjusted both laterally and longitudinally to utilize its entire surface.

Having thus described my invention, what I claim, and desire to secure by Letters Patent, is—

A saw-jointer comprising the yoke 2, formed with the integral parallel arms 3 4, having 100

the alined shoulders 6 6, in combination with the guide-plates 9 and 10 formed with the enlarged orifices 13 13, the thumb-screws 11 11' and 12 12' provided with collars 14, and adapted to secure said guide-plates to said arms so that the former may be both laterally and longitudinally adjustable thereon, the set-screw 8 secured in said yoke, and the file-blade 7 adjustably secured on said shoulders

by said set-screw 8, substantially as shown 10 and described.

In testimony whereof I hereunto affix my signature in presence of two witnesses.

RUFUS D. KING.
